H. KISTER

WATERPROOF CIGARETTE CONTAINER

Filed Aug. 29, 1923

FIG. II

FIG. III

Inventor:

HARRY KISTER,

*By Arthur E. Davis,
Attorney.*

Patented Jan. 13, 1925.

UNITED STATES PATENT OFFICE.

HARRY KISTER, OF PHILADELPHIA, PENNSYLVANIA.

WATERPROOF CIGARETTE CONTAINER.

Application filed August 29, 1923. Serial No. 659,861.

To all whom it may concern:

Be it known that I, HARRY KISTER, a citizen of the United States, residing at Philadelphia, in the county of Philadelphia and State of Pennsylvania, have invented a certain new and useful Improvement in Waterproof Cigarette Containers, whereof the following is a specification, reference being had to the accompanying drawings.

It is the object of my invention to provide a container which may be conveniently carried by a person clad in a bathing suit and which may be worn in salt water without corrosion, and which displays its contents so that the latter may be seen without opening the container. As hereinafter described, my invention includes a container comprising a phial of transparent glass horizontally wider one way than the other and curved to fit the chest of the wearer and provided with a lid of the same material; said phial having means arranged to pivotally connect it with a necklace so that it may hang from the neck of the wearer as a pendant, and also having means to securely detain said lid in closed, but readily removable, position; said lid having a flange arranged to extend downwardly into the phial and carrying a resilient rubber gasket adapted to seal the joint between the phial and the lid. Such supporting and connecting means includes a band, conveniently formed of metallic wire, extending around said phial and having, at the opposite narrow sides of the latter, eyes for pivotal engagement with the ends of a necklace and having, at the opposite wider sides of the phial, and near the narrow sides thereof, two pairs of eyes, each pair adapted to pivotally engage a swing bail respectively adapted to detachably engage the opposite ends of said lid; the latter having respective cam inclines with detent notches at the top thereof adapted to detachably detain the respective bails with the lid in closed position.

My invention includes the various novel features of construction and arrangement hereinafter more definitely specified.

In said drawings; Fig. I is a front elevation of a necklace and a pendant phial and its appurtenances embodying my invention.

Fig. II is a plan view of said phial showing the relative position of the six pivot eyes with which it is provided.

Fig. III is a plan view of a modified form of annular band for the phial.

In said figures; the container includes the transparent glass phial 1 horizontally wider one way than the other, and having its opposite wider walls 2 and 3 cylindrically curved respectively inward and outward, as indicated in Fig. II, to fit the chest of the wearer, and having its opposite narrower vertical walls 4 and 5 both cylindrically curved outward; all corners of said phial being rounded as indicated. The phial lid 6 is also conveniently formed of transparent glass and has the annular flange 7 fitted to extend downwardly within said phial and carrying the resilient soft rubber gasket 8 adapted to seal the joint between said phial and lid.

Said phial 1 has transverse ribs 9 and 10 projecting from its respectively opposite wider walls 2 and 3, at the top thereof, forming a seat for said gasket of greater extent than the thickness of said phial walls and also serving to retain the annular band 12 which is conveniently formed of wire encircling said phial and forming six pivot eyes. Said pivot eyes include two lace eyes 14 and 15 respectively at the opposite narrower sides of said phial, and four bail eyes; two, 16 and 17 adjoining the narrow wall 4 and two, 18 and 19, adjoining the narrow wall 5. Said lace eyes 14 and 15 are respectively pivotally connected with the opposite end bights 20 and 21 of the necklace 22 which may be a flexible connector of any kind, conveniently an elastic fabric. Said bail eyes 16 and 17 pivotally engage the opposite end loops 24 and 25 of the swing bail 26. Said bail eyes 18 and 19 respectively engage the opposite end loops 28 and 29 of the similar swing bail 30. Said bails 26 and 30 are so proportioned and arranged that they fit as closely to the container as may be with freedom to oscillate over their respective ends of said lid 6; the bights 31 and 32 of said bails being adapted to ride upon the curved cam inclines 34 and 35 of said lid so as to draw the latter down upon the gasket 8 to compress the latter, until the bails are engaged in the respective bail notches 36 and 37 in said lid cams in which they are normally detained against accidental displacement by the pressure of said gasket 8.

Although I have found it convenient to make the annular bands with the six eyes aforesaid of wire; I find that such construction of corrosion resisting metal is more

costly than if said bands be made of celluloid or any suitable material which may be formed in one piece as indicated in Fig. III. An advantage of such a celluloid band 5 is that it may be formed with an opening 40 slightly smaller than the horizontal dimensions of the phial which it is to encircle and be expanded by immersion in hot water until it will slip over the phial. Whereupon, 10 upon cooling to atmospheric temperature; it will grip the phial so that it cannot be accidentally displaced.

It may be observed that in each form of 15 my invention above described, the phial is provided with means affording a plurality of pivot recesses; certain of which afford means for connecting bails with the phial to engage the lid, and it is to be understood that I do not desire to limit my claims to 20 any specific material for forming such recesses.

Although I prefer to make both the phial and lid of transparent glass; it is to be understood that they may be made of other 25 material and, although I have found it convenient to make the container of the proportions shown to hold an ordinary sized pack of cigarettes; it is to be understood that containers in accordance with my invention 30 may be made of different sizes. Therefore, I do not desire to limit myself to the precise details of construction and arrangement herein set forth as it is obvious that various modifications may be made therein, without 35 departing from the essential features of my invention, as defined in the appended claims.

I claim:

1. A water-proof cigarette container, arranged to be worn as a necklace pendant; including a substantially flat transparent glass phial, a transparent glass lid, for said phial, having an annular flange fitted to said phial; a resilient gasket, carried by said lid and adapted to seal the joint between said 40 phial and lid; outwardly extending means at the top of said phial forming a seat for said gasket; an annular band, encircling said phial beneath and retained by said seat forming means, and having six pivot eyes, 45 including two lace eyes and four bail eyes; a necklace pivotally connected with said lace 50

eyes; two swing bails respectively having end loops engaging said bail eyes, and arranged to swing over said lid; and separate bail notches on said lid arranged to receive 55 and detain the respective bails when said gasket is compressed to seal the joint between said phial and lid.

2. A water-proof cigarette container, arranged to be worn as a necklace pendant; including a substantially flat transparent 60 glass phial; a transparent glass lid, for said phial, having an annular flange fitted to said phial; a resilient gasket, carried by said lid and adapted to seal the joint between said 65 phial and lid; outwardly extending means at the top of said phial forming a seat for said gasket; means affording a plurality of pivot recesses on said phial; a necklace pivotally connected with two of said recesses; 70 and two swing bails each respectively connected with other of said recesses.

3. A water-proof cigarette container, arranged to be worn as a necklace pendant; including a substantially flat transparent 75 glass phial; a transparent glass lid, for said phial, having an annular flange fitted to said phial; a resilient gasket, carried by said lid and adapted to seal the joint between 80 said phial and lid; outwardly extending means at the top of said phial forming a seat for said gasket; means on said phial, beneath said seat forming means, affording four pivot recesses arranged in pairs upon 85 opposite sides of said phial adjacent the opposite edges thereof; two swing bails each having means engaging two of said pivot recesses, and arranged to swing over said lid; and means on said lid including cam 90 inclines at opposite ends thereof, having respective bail notches at their upper ends adapted to receive and detain the respective bails when said gasket is compressed to seal the joint between said phial and lid.

In testimony whereof, I have hereunto 95 signed my name at Philadelphia, Pennsylvania, this twenty-seventh day of August, 1923.

HARRY KISTER.
Witnesses:

ARTHUR E. PAIGE,
CAROLINE E. REUTER.
